CLAIM

The ornamental design for a bicycle theft deterrent device with shackle and crossbar, as shown and described.

DESCRIPTION

The patent or application file contains a least one drawing executed in color. Copies of this patent or patent application publication with color drawing(s) will be provided by the Office upon request and payment of the necessary fee.

FIG. 1 is a perspective view of a bicycle theft deterrent device with shackle and crossbar showing front, top, and right sides;

FIG. 2 is a perspective view of a bicycle theft deterrent device with shackle and crossbar showing front, bottom, and left sides;

FIG. 3 is a top view thereof;

FIG. 4 is a bottom view thereof;

FIG. 5 is a rear view thereof;

FIG. 6 is a front view thereof;

FIG. 7 is a right side view thereof; and,

FIG. 8 is a left side view thereof.
